UNITED STATES PATENT OFFICE.

HAROLD CARLE, OF BUFFALO, NEW YORK, ASSIGNOR, BY MESNE ASSIGNMENTS, TO VORTEX MFG. CO., OF CHICAGO, ILLINOIS, A CORPORATION OF ILLINOIS.

CUP BLANK.

Application filed June 7, 1924. Serial No. 718,429.

This invention relates to blanks for forming paper drinking vessels.

An object of this invention is to provide an improved blank which may be formed into a conical vessel for drinking or similar purposes, which may be easily fabricated into a cup and which will produce a strong tight cup with a minimum consumption of paper.

10 Another object of the invention is to provide an improved blank from which a cup may be formed completely and tightly closed at the apex, without a tab.

Other objects of the invention will in part 15 be obvious and will in part appear herein-after.

On the drawings:

Figure 1 is a developed plan view of a cup blank embodying the principles of this 20 invention.

Figure 2 is a front view of a formed cup. It has heretofore been proposed to construct paper drinking vessels of general segmental shaped sheets having a projection at 25 the apex of the segment which may be folded around the apex of the cup when formed to close the apex. Such cups are objectionable by reason of the fact that difficulty is experienced in maintaining a water-tight joint at 30 the apex of the cup, and the projecting tab at the apex of the blank prevents the economical cutting of the blank from the paper sheet.

It has also been proposed to construct 35 paper drinking cups having the center of the arc wholly within a sheet of paper in order to make a water-tight joint at the apex of the cup, as shown for example in the patent to Sharon, No. 1,184,916, but such cups have not been commercially successful 40 because among other difficulties the excess of paper produces an undue thickness particularly at the apex and the blank is unduly wasteful of paper in the cutting. Furthermore with such construction, the center has 45 been spaced so far from the edge that when the blank was folded in conical shape, the free edge of the blank could not be adhesively secured to the opposed side of the blank, but instead was folded back upon itself so 50 that a folded edge was juxtaposed to the opposed side. Such a folded edge in cups of this character does not satisfactorily adhere.

In accordance with the present invention, 55 it is possible to construct a blank which will

be tightly closed at the apex without a tab and which will be simple to construct and economical in manufacture.

The blank 1 is of general segmental shape having an arcuate side 2 struck from a center 3. One of the remaining sides as 4 may be substantially radial, passing, however, outside of and slightly spaced from the center 3. The other side of the blank 5 is materially spaced from the radius 6 and may 60 be substantially parallel to it. The sides 4 and 5 continue until they substantially meet each other as at 7, although it will be obvious that the blank may be rounded at the intersection 7 if desired.

In the manufacturing of a conical cup 70 from this blank, the apex of the cone will be placed substantially at the center 3 so that it is completely within the area of the blank. Thus there is no opening at the apex to be 75 closed. At the same time by reason of the proximity of the center 3 to the side 4, the blank may be formed directly into a cone with the edge 4 flat against the opposed side of the blank as at 6 without tearing of the 80 paper at the apex. A very short crimped or kinked extension, or tip, limited in length by the distance between the center 3 and the edge 4, is formed; and this extension is bent or folded about the apex of the cone and is 85 overlapped by the portion of the blank shown on the left of the radius 6 in Figure 1 of the drawings when this overlapping portion of the blank is wrapped about the 90 cone externally of the edge 4.

The blank is folded to the point where the side 4 slightly over-laps the opposite side 5 as at 8 so that the material between the line 8 and the edge 5 serves as an over-lap which may be pasted around the cup to hold it 95 tight, and by reason of the smaller diameter of the apex of the cup, this projecting portion will lap far around the cup at the apex, so that the cup is materially strengthened and secured thereby.

That portion 9 of the line 4 which is beyond the center when the blank is constructed proportionately as shown, will lie upon the cup along one of the elements of the cone, thereby improving the appearance of the 105 cup.

Having described my invention, what I claim as new and desire to secure by Letters Patent, is:

1. A blank forming a drinking cup com- 110

prising a sheet bounded by an arcuate edge, and two non-radial edges of different lengths including the center of the arc between them, the longer of said non-radial edges meeting the shorter non-radial edge at a point beyond the center of the arc to form a relatively wide overlap portion, the said longer non-radial edge being so close to the center of the arc that when the major portion of said longer non-radial edge is revolved about said center as the apex of a cone to coincide with a radius a short crimped extension is formed, said extension being adapted to fold about the apex and to underlie said overlap portion when said overlap portion is brought into its final position externally of said longer non-radial edge.

2. A blank for forming a drinking cup comprising a sheet bounded by an arcuate

edge, and two substantially straight non-radial edges of different lengths including the center of the arc between them, the longer of said straight edges meeting the shorter straight edge at a point beyond the center of the arc to form a relatively wide overlap portion, the said longer straight edge being so close to the center of the arc that when the major portion of said longer straight edge is revolved about said center as the apex of a cone to coincide with a radius a short extension is formed, said extension being adapted to fold about the apex and to underlie said overlap portion when said overlap portion is brought into its final position externally of said longer straight edge.

In testimony whereof I affix my signature.
HAROLD CARLE.
